US0D1086453S

(12) **United States Design Patent** (10) **Patent No.:** **US D1,086,453 S**
(45) **Date of Patent:** **** Jul. 29, 2025**

(54) **MEDICAL BOTTLE ADAPTER**

(71) Applicant: **F. Hoffmann-La Roche AG**, Basel (CH)

(72) Inventors: **Neil Bentley Cammish**, Basel (CH); **Thomas Thueer**, Basel (CH); **Ian James Matthews**, Basel (CH)

(73) Assignee: **F. Hoffmann-La Roche AG**, Basel (CH)

(**) Term: **15 Years**

(21) Appl. No.: **29/918,076**

(22) Filed: **Nov. 24, 2023**

Related U.S. Application Data

(63) Continuation of application No. 35/513,802, filed on Dec. 15, 2021 (U.S. filing date under 35 U.S.C. 384), and having an international filing date of Dec. 15, 2021, now abandoned.

(57) **CLAIM**

The ornamental design for a medical bottle adapter as shown and described.

DESCRIPTION

FIG. 1 is a bottom view of a medical bottle adapter showing the claimed design;

FIG. 2 is a bottom perspective view thereof;

FIG. 3 is another bottom perspective view thereof;

FIG. 4 is a top perspective view thereof;

FIG. 5 is a right view thereof the left side being a mirror image; and,

FIG. 6 is a top view thereof.

1 Claim, 6 Drawing Sheets
